UNITED STATES PATENT OFFICE.

FRIDOLIN POLZER, OF NORWALK, CONNECTICUT, ASSIGNOR TO THE E. H. HOTCHKISS COMPANY, OF NORWALK, CONNECTICUT, A CORPORATION OF CONNECTICUT.

LOADING DEVICE FOR WIRE-STAPLING MACHINES.

Application filed February 9, 1925. Serial No. 7,815.

This invention relates to feeding devices for wire staple machines, and has for an object to provide a device for facilitating the loading of the wire staples in the machine to prevent loss of time and trouble, and also to prevent loss of the staples during the loading operation.

With the foregoing and other objects in view, I have devised the construction illustrated in the accompanying drawing forming a part of this specification, similar reference characters being employed throughout the various figures to indicate corresponding elements. In this drawing,

Fig. 1 is a side elevation of a stapling machine showing the method of using my improved loading device.

Fig. 2 is a top plan view of the rear end thereof.

Fig. 3 is a top plan view of the loading device.

Fig. 4 is a longitudinal section thereof substantially on line 4—4 of Fig. 3.

Fig. 5 is a transverse section substantially on line 5—5 of Fig. 3.

Fig. 6 is a longitudinal section through a loading device of a slightly different construction, the section being taken substantially on line 6—6 of Fig. 7.

Fig. 7 is a rear end view of the device shown in Fig. 6, and

Fig. 8 is a top plan and side elevation of the retaining clip on an enlarged scale.

I have shown merely in outline a stapling machine for use in setting substantially U-shaped wire staples, the machine comprising a base 10, and a housing 11, pivoted to the base at 12 and containing the mechanism for feeding and setting the staples. This mechanism is not shown as it forms no part of my present invention, but it is operated by the usual plunger 13 which is reciprocated by the hand knob 14 and spring 15 in the well known manner. In this type of machine there is a staple support or guide, usually comprising a substantially rectangular bar 16, which projects through the rear end of the machine and on which the staples are placed for supplying the feeding and setting mechanism. The staples are fed to the machine by placing them on the rear end of this support or guide and then sliding them along this guide into the machine.

For facilitating this operation both to

save time and trouble and to prevent loss of staples during this feeding operation I have devised the feeding devices shown in Figs. 3 to 8. In the construction shown in Figs. 3 to 5 the device comprises a support 17 of sheet metal bent to substantially U-shape in 55 cross section and of a length to support the desired number of U-shaped staples 18 placed side by side so that they embrace the sides and top of the support as shown. Heretofore it has been difficult to prevent 60 these staples from dropping off the support while feeding them to the machine. In the present construction I overcome this difficulty. The top 19 of the support is slit longitudinally by two spaced cuts 20 and 70 the metal 21 between these two cuts is forced upwardly above the plane of the top 19 a sufficient distance to allow the staples to 75 pass between it and the top, but it is sufficiently close to the top to prevent their dropping off. One end of this retaining member is left attached to the top as shown at 22 while the other end 23 is free so that the staples can pass off or on under this free end. To strengthen this strip or retaining 80 member it is provided with a longitudinally extending rib 24 pressed into the strip and preferably extending downwardly so as to provide a groove 25 in the top of the strip, altho of course it may extend upwardly if 85 desired. This groove, however, is stopped short of the free end 23 for a purpose presently to be described. As the formation of this retaining member 21 weakens 90 the top portion of the support the metal of this top portion is strengthened adjacent the opposite ends thereof by transverse ribs 26, but these ribs do not extend the entire width of the top because in that case the staple would fall into them as they pass 95 off this support.

As indicated in Figs. 3 and 4 the staples 18 are placed on the support side by side embracing the top and sides of the support, but they lie under the retaining member 21 which holds them against the top of the support. To retain these staples on the support and prevent their passing off under the free end of the retaining member 21 during handling and transportation means is provided for holding them on the support, which in the present instance, comprises a metal clip 100 105 bent upon itself so that it embraces the

ends of the support 17 and the retaining member 21, and it is held in position on the support by means of a downwardly extending projection 28 on its upper end extending into the end of the groove 25 and engaging the closed end of this groove to prevent the clip sliding off. The other end of the clip extends around under the top 19 of the support and its free end 29 is bent around the transverse rib 26 as shown in Fig. 4. The clip is thus securely fastened on the support and will prevent the staples falling off.

When it is desired to feed the staples to the machine the clip 27 is removed by lifting its upper free end away from the retaining member 21 and to free the projection 28 from the groove 25. The clip may then be removed entirely so that the staples may be slid off the support. After the clip has been removed the end of the support 17 is placed against the projecting end of the staple support or guide 16, as shown in Figs. 1 and 2, and to better hold this staple support 17 in position the projecting end of the guide 16 is reduced somewhat as shown at 30, so that it may extend between the sides and the top of the support 17. The staples may then be fed into the machine by merely pushing against those at the outer end of the support 17 and sliding them along this support onto the guide 16. During this operation they are guided and prevented from dropping off the support by the retaining member 21.

In Figs. 6 and 7 I have shown a slightly different construction. In this construction instead of slitting the top of the support 17 to form the retaining member 21 this member is a separate element 31 which is secured to the U-shaped staple support 32, which corresponds to the support 17 in the first form. By cutting one or more transverse slits adjacent one end of the top of this member and bending the metal between the slits upwardly, as shown at 33, and then inserting the end 34 under the upwardly bent strips the retaining member is held in position. Otherwise the function and operation is the same, the retaining member being provided with a strengthening rib 35 and groove 36 stopping short of its free end the same as in the first form to receive the projection 28 of the clip 27, and the support 32 is provided with an inwardly extending rib 37 corresponding to the rib 26 in the first form to assist in holding the clip 27 in position.

Having thus set forth the nature of my invention, what I claim is:

1. A loading device for wire staple machines comprising a substantially U-shaped member adapted to carry a plurality of U-shaped wire staples embracing the top and sides thereof and arranged to allow the staples to slide longitudinally of the member and off one end during the loading operation, and a holding strip secured to the member adjacent one end thereof and extending longitudinally thereof above the staples to retain them on the member during said sliding movement, said strip being disconnected from the member at the opposite end to allow the staples to slide off the member at that end.

2. A loading device for wire staple machines comprising a sheet metal support substantially U-shape in cross section adapted to carry a plurality of U-shaped staples, the top of said support having two spaced cuts extending longitudinally thereof with the metal between the cuts forming a staple holding strip raised above the top of the member to allow the staples to be mounted between them, said strip being secured to the support at one end and spaced therefrom at the other end, and a removable clip at the latter end to retain the staples on the support.

3. A loading device for wire staple machines comprising a sheet metal support substantially U-shape in cross section adapted to carry a plurality of U-shaped staples, a retaining member extending longitudinally of the support and spaced a short distance above the top thereof for insertion of the staples between the support and member, said member being attached to the support at one end and free from the support at the other end also being provided with a depression adjacent said latter end, the top of the support being provided with a transverse rib projecting inwardly adjacent said free end, and a metal clip bent upon itself to embrace the ends of the support and retaining member to retain the staples on the support, said clip being provided with a projection to extend into said depression and also provided with a portion engaging the rear side of said rib to retain the clip on the support.

In testimony whereof I affix my signature.

FRIDOLIN POLZER.
